UNITED STATES PATENT OFFICE.

ORVILLE G. HALLIBURTON, OF DALLAS, TEXAS.

COMBUSTION DEVICE.

1,135,688.

Specification of Letters Patent. Patented Apr. 13, 1915.

Application filed September 8, 1914. Serial No. 860,775.

To all whom it may concern:

Be it known that I, ORVILLE G. HALLIBURTON, citizen of the United States, residing at Dallas, in the county of Dallas and State of Texas, have invented certain new and useful Improvements in Combustion Devices, of which the following is a specification.

This invention relates to new and useful improvements in combustion devices.

The object of the invention is to provide two burner members arranged to be operated either in unison or separately together with means for controlling the amount of fuel oil fed to each member.

Other objects of the invention are, the provision of a burner base adapted to set upright in the fire box of a stove and constructed to support the burner members; generating pans mounted on the base and projecting laterally therefrom beneath the burner members; means for draining the pans and preventing flooding of the fire box; and means for facilitating the vaporizing of the oil.

Another object of the invention resides in the production of a combustion device possessing strength, durability and simplicity; and designed for minimum wear and arranged to be constructed at a minimum expense.

Referring now particularly to certain novel features of the invention, an example is described in the following specification and illustrated in the accompanying drawings, wherein:

Figure 1 is a side elevation of the combustion device in position in a fire box of a stove, component parts of the latter being shown in section, Fig. 2 is a plan view of the device, Fig. 3 is a transverse section taken on the line X—X of Fig. 1, Fig. 4 is a sectional detail of one of the pans, and Fig. 5 is a transverse sectional detail of the rear burner member feed pipe.

In the drawings the numeral 1 designates a metal base constructed to fit in the fire box of a stove and rest on the grate as shown in Fig. 1. The base has an elongated central web 2 connecting its ends 1^a. Two burner members 3 are mounted on the base and each comprises a length of pipe bent to form a U-shaped vaporizer, the parallel arms 4 and 5 of each member in operative position are disposed horizontally and one

above the other, the lower arm 5 of each being provided with a small hole or orifice 6 over which a spreader 7 is mounted on the upper arm 4. I have designated the member 3^a at the left of Fig. 1 as the front burner member and the other as the rear burner member 3.

The members 3 and 3^a are supplied by feed pipes 8 and 9, the former leading to the front member and the latter to the rear member. The feed pipes are disposed on opposite sides of the web 2 and each is connected to its respective burner member by a vertical pipe 10 in which a union 11 is included. By means of the unions it is possible to remove the members 3 and 3^a without disturbing the pipes. The members are alined on the same side of the web and parallel thereto, the pipe 9 being connected through the web with its respective pipe 10 as shown in Figs. 1 and 2.

The burner members being at one side of the web are disposed each over a pan 12 mounted on the web and projecting laterally therefrom. Each pan is located so that the center of each hole 6 and the center of the pan will be substantially in a vertical line.

Each pan has a hopper bottom as is best shown in Fig. 4. From the center of each pan a nipple 14 depends and is received in the end of a drain pipe 15. The pipes 15 are connected to a pipe 16 extending out of the fire box and having a valve 17 as shown in Fig. 1. It is apparent that any oil leaking from the burner members when the latter are not in operation will be caught in the pans and carried off by the pipes 15 and 16 when the valve 17 is open.

The feed pipes 8 and 9 extend through the front end 1^a of the base 1 and each is connected to a regulating valve 18 which is disposed on the outside of the stove. The valves 18 are connected by a pipe 19 which in turn has connection with a pipe 20. Fuel oil is fed from a reservoir (not shown) by means of the pipe 20. The reservoir or other supply is located above the burner members 3 and 3^a, a gravity feed thus being had.

In operating the device the valve 17 is closed and the valves 18 opened. Fuel oil passes from the pipe 19 into each valve and then into the feed pipes 8 and 9. In the pipe 9 a wire 21 is disposed which aids in 110

the generation of a gas or the vaporization of the oil. The oil flows from the pipes 8 and 9 through the pipes 10 to the burner members 3 and 3^a and out of the holes 6. 5 After a small quantity of oil has accumulated in each pan it is ignited. In a short time the burner members become heated and the oil therein is turned into gas, a flame being ignited at each hole 6. The pipe 9 will 10 become hot so that the wire 21 will act to more evenly distribute the heat and prevent the flames from overheating said pipe. In the arms 4 light wires 22 are also disposed to distribute the heat and facilitate the 15 operation of the device.

The flames may be deflected by the spreaders to either side and are equally radiated. It will be observed that if desired either 20 burner member may be operated or both may be used; also that the burner members may be individually controlled and regulated. The base 1 is very useful as it supports the parts in fixed relation and can be placed in the stove without much labor and 25 alteration of the latter. When the burners are not in use the valve 17 is opened and any drippings will be carried off, thus preventing flooding of the fire box.

What I claim, is:

1. The combination in a combustion device, of a supporting base having an elongated central web, feed pipes disposed on each side of the web and mounted in the base, a pair of burner members mounted on the same side of the base web above the same and each connected to a feed pipe, valves connected to each feed pipe, and heating pans mounted on the base web under the burner members.

2. In a combustion device, the combination with a supporting base, a pair of retort burner members mounted on the base, and pipes for feeding fuel oil to the members, of heating pans mounted on the base under the burner members and each having a dished bottom, a drain pipe extending under the pans, pipes connecting the pans with the drain pipe, and a valve located in the drain pipe.

In testimony whereof I affix my signature in presence of two witnesses.

ORVILLE G. HALLIBURTON.

Witnesses.
